UNITED STATES PATENT OFFICE.

FRANKLYN L. MATHIES, OF ROCHESTER, NEW YORK, ASSIGNOR TO ROYAL TYPE-WRITER COMPANY, INC., OF NEW YORK, N. Y., A CORPORATION OF NEW YORK.

COMBINED FRONT-LEVER AND TYPE-BAR SUPPORT.

1,217,325.

Specification of Letters Patent.

Patented Feb. 27, 1917.

Application filed November 27, 1915. Serial No. 63,750.

To all whom it may concern:

Be it known that I, FRANKLYN L. MATHIES, a citizen of the United States, residing in Rochester, in the county of Monroe and State of New York, have invented certain new and useful Improvements in Combined Front-Lever and Type-Bar Supports, of which the following is a specification.

10 This invention relates to so constructing and combining certain parts of typewriting machines as to effect a considerable saving in material and time in the manufacture of such machines.

15 To exemplify, in the Royal typewriter for instance, the support for the front levers of the type bar actuating devices consists of a bar arranged laterally in the machine and by suitably faced end bearings is attached 20 to counter faced bearings formed on the inner sides of the side walls of the main frame; the type bar head rest also consists of a separate bar curved in two directions to correspond to the arcuate arrangement of 25 the type bar heads when at rest, and is also, by suitable faced bearings, secured to the side walls of the main frame. This bar is adjacent the front lever support and these two devices or parts of the machines always 30 occupy the same positions relative to one another.

These parts in the present practice of manufacture are cast or formed separately, 35 tooled separately and are separately set, secured and adjusted in operative positions in the main frame. By this invention they are integral, being cast or formed as a unit, and so require one tooling operation as regards 40 the bearing surfaces, one means of attachment to the main frame and one adjusting operation.

In the accompanying drawings to which reference will now be had to more fully describe the invention:

45 Figure 1 is a perspective view of the combined front lever support and type bar head rest, looking in an angular direction downwardly thereon, and:

Fig. 2, a central cross-section of the same applied in operative position to a machine; 50 said view illustrating so much of the other parts of the machine as is necessary to show the relation of the device of this invention thereto.

55 In Fig. 2 parts of a Royal typewriting

machine are illustrated comprising key levers 4, type bars 5, type bar heads 6, rear links 7 provided with springs, front levers 8 connected to short arms 9 of the type bars by links 10 and vertical link 11 connecting the 60 key levers to the front levers 8. 12 designates a side wall of the main frame, 13 the platen, 14 the type bar head rest pad and 15 the front dust guard.

The conformation of the central part of 65 the combined front lever support and type bar head rest is clearly shown in section in Fig. 2. The front portion 16 is straight extending fully across the machine, the upper surface thereof being inclined to correspond 70 to the shape of the front dust guard 15. On the underside is a longitudinal ridge or rib 17 which is provided with transverse slots for the reception of the front levers 8, constituting what is known as a comb, and said 75 rib is longitudinally bored for the reception of a rod 18 which, passing through holes in the levers, acts as a bearing for them and holds them in operative position on the support. At the center this front portion 16 80 extends rearwardly and downwardly terminating in the central part of the bed 19 of the type bar head rest. In both directions from the center, the bed 19 curves in both upward and rearward directions correspondingly to the arcuate arrangement of the type 85 bar heads 6 as they rest on the pad 14 which is attached to the bed 19 of the head rest. The front lever support and the bed 19 of the head rest are connected together from 90 the center to the ends of the bed 19 by webs 20, said bed terminating considerably within transverse planes including the ends of the front lever support, as clearly shown at Fig. 1. The ends 21 of the lever support 95 are adequately tooled or suitably finished to fit snugly between the bearing surfaces on the inner sides of the side walls 12 of the main frame, to which they are secured by screws or in any other ordinary manner. 100

Of course it will be understood that the controlling feature of this invention may be exercised in constructing adjacent separate parts of machines other than the front lever support and type bar head rest of the 105 Royal typewriting machine to which it is applied as herein described.

I claim:

1. An integral front lever support and type bar head rest, comprising a straight bar 110

provided at the front with bearings for the front levers and with an arcuate rest bed for the heads of the type bars extending rearwardly from said front lever support and 5 removable bodily with said support from the machine frame.

2. An integral front lever support and type bar head rest, comprising a straight bar having its upper surface inclined forwardly and provided at the front with bearings for the front levers and with an arcuate rest bed for the heads of the type bars formed integrally with said support and extending rearwardly from a downwardly arranged portion of the central part of said front levers support.

3. In a typewriting machine, a combined front lever support and type bar head rest, comprising a straight bar provided at the front with bearings for the front levers and a rest for the heads of the type bars integrally formed, said type bar head rest being curved in two directions with its ends terminating between and within planes including the ends of the lever support.

4. In a typewriting machine, a combined front levers support and type bar head rest, comprising a straight bar provided at the front with bearings for the front levers and a rest for the heads of the type bars integrally formed, said type bar head rest being curved in two directions with its ends terminating between and within planes in-

cluding the ends of the lever support and means at the ends of the front lever support 35 for connection with the main frame of the typewriting machine.

5. A combined front lever support and type bar head rest comprising a straight bar provided at the front with bearings for the front levers and at the rear with an integral arcuate rest bed for the heads of the type bars the middle portion of which bed is depressed below the upper face of said bar and the opposite end portions of which are 45 supported by integral webs extending upwardly from the rear portion of the bar.

6. A combined front lever support and type bar head rest comprising a straight bar slotted at the front to receive the front levers 50 and formed integrally at the rear with an arcuate rest bed for the heads of the type bars the middle portion of which is depressed below the plane of the upper face of said bar and is disposed in rear thereof 55 while the end portions which are formed integrally with the bar extend upwardly from the middle portion of the bed near the opposite ends of said bar.

In testimony whereof, I have hereunto 60 subscribed my name.

FRANKLYN L. MATHIES.
